UNITED STATES PATENT OFFICE.

CROWELL M. CLANCY, OF WALLACEBURG, ONTARIO, CANADA.

HOOP-MACHINE.

SPECIFICATION forming part of Letters Patent No. 241,928, dated May 24, 1881.

Application filed October 18, 1880. (No model.)

To all whom it may concern:

Be it known that I, CROWELL M. CLANCY, of Wallaceburg, Kent county, and Dominion of Canada, have invented an Improvement in 5 Hoop-Machines, of which the following is a specification.

My invention relates to improvements in hoop-machines; and it consists in the peculiar construction and arrangement of the parts, as 10 herein more fully set forth.

In the drawings, Figure 1 is a side elevation of my improvement. Fig. 2 is a section on the line *x x* in Fig. 1. Fig. 3 is a plan view of the bottom, taken on the line *y y* in Fig. 1. Fig. 15 4 is a detached plan view of the horizontally-cutting knife with its attachments. Fig. 5 represents the manner of operating the three knives.

In the accompanying drawings, which form 20 a part of this specification, A B C represent a suitable frame to support and carry the operating parts of the device. To the lower part of the frame is journaled the main shaft D, to which motion may be communicated from any 25 suitable source. To each end of this main shaft D are secured the eccentrics E F, which, by means of suitable connecting-rods, G, give an alternate reciprocating motion to the cross-heads H I, carrying the knives J K. These 30 cross-heads have their motion upon the slides L M, suitably secured to a support, N.

O represents a table, upon which the material to be cut is placed; and P is a feed-guide, by means of which the plank or cant is fed to 35 the operating-knives, and this feed may be actuated by any of the known mechanical devices in use for giving an intermittent motion thereto, as may be desired.

The machine constructed as above described 40 is all that is required in cutting hoops from a plank having a thickness equal to the width of the hoop desired. The plank being placed upon the table and fed up to the point for cutting, the knife J, having a diagonal cut to 45 give the required bevel, (and this knife should be adjustable to any desired bevel,) makes its first cut, being actuated thereto by the eccentric movement from the main shaft D, and on this knife receding from its cut, having left a

beveled edge to the plank, the knife K makes 50 its vertical cut, the plank having been fed up the proper distance, thereby severing the second hoop, and so on, the knives giving an alternating vertical and diagonal cut until the plank is used up. 55

Where it is designed to cut bevel hoops from a cant the eccentrics E F are so set as to limit the throw of the knives J K to the width of the hoop desired, and the cant being in position on the table the operation of cutting the 60 hoops is commenced in the manner already described; but in order to finish such hoops, by cutting them from the cant at the bottom of the stroke of the knives which cut the straight and bevel sides thereof, requires additional mechanical devices for operating a knife having a horizontal cut in oscillating lines at the base of the cuts which form the sides of the hoops. To accomplish this end a spur-wheel, Q, upon the main shaft D gives 70 motion to the counter-shaft S through the spur-wheel R. Upon or near the end of this counter-shaft S is secured the bevel-pinion T, which gives motion to a like wheel, U, upon the vertical shaft V, suitably journaled to the side 75 of the frame. Upon the top of this shaft V is secured the wheel W, to which the horizontally-acting knife X is adjustably secured by means of the slot *a* and wrist-pin *b*. A similar arrangement at the opposite side of the 80 frame may be provided to give motion to the opposite end of the knife, the two wrist-pins being so arranged as to give a horizontally-oscillating motion to the knife; or such motion may be obtained by one connection, as described, and the opposite end of the knife by 85 means of the curved slot *c* engaging with the stud *d*.

By this arrangement, after the knives have cut the sides of the hoops, the knife X is thrown 90 forward horizontally to cut such hoops off at their bottom edges, the oscillating movement described giving a drawing-cut to the knife.

What I claim as my invention is—

1. The combination, with the shaft D, provided with the eccentrics E F, of the slides L M, cross-heads H I, knives J K, set at an inclination to each other, as described, and

connecting-rods G, whereby an alternate reciprocating motion is given the knives, substantially as described.

2. The combination, with the shaft D, provided with the eccentrics E F, and spur-wheel Q, of the slides L M, cross-heads H I, knives J K, counter-shaft S, having spur-wheel R and bevel-pinion T, shaft V, carrying the bevel-

gear U and wheel W, and knife X, having the slots a c, substantially as described, and for the purpose set forth.

CROWELL M. CLANCY.
